UNITED STATES PATENT OFFICE.

GEORGE W. N. YOST, OF NEW YORK, N.Y., ASSIGNOR, BY MESNE ASSIGNMENTS,
TO THE AMERICAN WRITING MACHINE COMPANY, OF SAME PLACE.

TYPE-WRITING MACHINE.

SPECIFICATION forming part of Letters Patent No. 341,089, dated May 4, 1886.

Application filed July 12, 1880. Serial No. 13,383. (Model.)

To all whom it may concern:

Be it known that I, GEORGE W. N. Yost, of the city, county, and State of New York, have invented Improvements in Type-Writing Machines, of which the following is a specification.

The nature of that part of the invention which comprises the subject-matter of this application may be described as follows: Heretofore numbering or hand stamps have been provided with two ribbon-spoools, alternately wound and unwound automatically through mechanism connected with the stamping-lever, and type-writers have heretofore been provided with a letter-space ratchet on a vibratory frame, and combined with a ratchet-wheel or with two racks arranged to slide one upon the other.

My improvement consists, mainly, in having one of the racks pivoted to hangers, so as to swing against the side of a rigid rack.

My improvement consists, also, in the two ribbon-spoools provided with ratchets and holding-pawl, in combination with the driving-pawl on each side of the letter-space vibratory frame, the adjusting-regulators, and their connecting-rod, as will be hereinafter described in connection with the drawings, and then pointed out in the claims.

Referring to the accompanying drawings, Figure 1 is a perspective view of a machine embodying the elements of the invention. Fig. 2 is a rear view of same. Fig. 3 is a front view with portions of the machine removed. Figs. 4 to 8 are views of detached parts of the machine, indicated thereon by letters, which are referred to hereinafter.

Of the drawings, A represents the main frame side plates of a type-writing machine; A², the top plate on the side plates, A; A³, a board or plate across on the bottom of the side plates, A; A⁴, a bar at the rear and bottom across on the side plates, A; A⁷, a cover over the front ends of the side plates, A; A⁸, a ring or circular orifice in the top plate, A²; A⁹, a rail on and across over the rear part of the top plate, A²; B, a hanger or series of hangers on the top plate, A², around the orifice A⁸, to which hangers will be suitably hinged a series of type-bars, which will be operated by a series of levers near the bottom and within the side plates, A, in the usual manner; G, a right-angled vibratory frame, hinged at the bottom

and rear between the side plates, A, with one part extended toward the front under the key-levers C and the other part extended toward the top plate, A²; G², a bar on the fore end of the vibratory frame G, across under and up against the key-levers C; I, a ribbon-spool on an axle in bearings under each end of the top plate, A²; I², an inking-ribbon on each ribbon-spool I, and extended up and across over the top-plate orifice A⁸ and type-bars; I³, a ratchet-wheel on the axle of each ribbon-spool I; J, a vertical post on each side of the lower part of the vibratory frame G; J², a driving-ratchet hinged on the upper end of each vertical post J and extended into engagement with the contiguous ribbon-spool ratchet-wheel I³; J³, an adjusting weight-arm on each ribbon-spool driving ratchet J², and extended toward the contiguous ratchet-wheel I³; K, a holding-ratchet hinged on each side plate, A, and extended into the teeth of the contiguous ribbon-spool ratchet-wheel I³; K², an adjusting weight-arm on each ribbon-spool holding-ratchet K and extended toward the contiguous ratchet-wheel I³; K³, an arm or lug parallel with the axis and extended out from each side of each ribbon-spool-holding ratchet K; L, an adjusting weight arm or regulator hinged to each side plate, A, and extended up next to and parallel with the contiguous ribbon-spool-holding ratchet K; L², a connecting-rod across over the type-key levers C in front of the type-bars and attached to the ribbon-spool ratchet-adjusting regulators L; M, a carriage over the top plate, A², and on the rails A⁹ A¹⁰; M², the front side bar of the carriage M, which is similar to the rear side frame thereof; M⁴, a traveling wheel on the carriage front side bar, M², and extended down to and on the top plate front rail, A¹⁰; M⁵, slide-bearings in the carriage rear side frame, M³, and on over the rear top-plate rail, A⁹; N, a cylindrical platen in bearings on the carriage M, across over the top-plate orifice A⁸; N², a spur-wheel on the end of the platen N; P, a combined lever and handle pivoted to the carriage front side bar, M², and curved with one end extended toward the rear and the other end down in front toward the key-levers C; P², a driving-ratchet pivoted on the upper end of the hand-lever P, and extended above the platen N and extended into the teeth of the platen spur-wheel N²; R, a toothed rack

rigidly attached to the carriage rear side frame, M³; R², hangers pivoted to and extended down from near each end of the carriage rear side frame, M³; R³, another toothed rack next to 5 and like the first rack, R, and pivoted to the hangers R²; R⁴, a spring attached at one end to the first toothed rack, R, and at the other to the second rack, R³; S, a long rod in bearings and extended from front to rear under 10 the bottom plate, A³; T, a spring coiled upon rod S; S², a long bar, something like a pendulum, pivoted to the hind end of the long rod S, and extended up abreast of the carriage M, and having a spring-tension toward the left; 15 S³, a pitman-like connecting-bar pivoted to the carriage M and to the upper end of the pendulum-like bar S²; U, a holding-ratchet on the upper end of the right-angled vibratory frame G and extended into the toothed racks 20 R R³; U², a pivot in the vibratory - frame ratchet U; U³, a stop on the upper end of the vibratory frame G on one side and below the pivot of the ratchet U; V, a curved spring paper-guide around the front part of each end 25 of the platen N; W, a bar in bearings across between the side plates, A, in rear of the levers which operate the type-bars; W², a vertical bar on each end of the pivoted cross-bar W, and extended up to the ribbon-spoils I; 30 W³, a slot in the upper end of each vertical bar W², into which is extended a flange of the contiguous ribbon-spool I; X, a rod in bearings parallel with the key-levers C in one of the side plates, A, and extended through the 35 contiguous vertical pivoted bar W²; Y, a crank on the hind end of the pivoted rod X, and Z an external screw-thread on the fore end of the crank-rod X, and through and within an internal screw-thread in the contiguous vertical hinged bar W².

As the depression and release of any type-key lever C or space-key lever H will vibrate the lower part of the vibratory frame G, so thereby it will vibrate the attached side posts, 45 J, and driving-ratchets J², which will turn the ribbon-spool ratchet-wheels each in turn, as one is thrown into and the other out of gear, and thereby turn the ribbon-spoils I and inking-ribbon I². In common type-writing machines the inking-ribbon is generally moved by transmitting mechanism connected directly with the carriage - driving power. This, however, is cumbersome, and subject to considerable friction; but in the invention described herein the ribbon movement is actuated directly from the vibratory frame G, and has no connection with the carriage-driving power.

To move the ribbon I² in one direction, the 60 ribbon-spool-driving ratchet J² on the side of that direction must be put in gear with its contiguous ratchet-wheel I³, and the opposite ratchet be put out of gear from its ratchet-wheel, and the reverse to move the ribbon in 65 the reverse direction. When either weight-arm or regulator L is turned and let fall toward the contiguous ratchet - wheel I³, the

weight-arms K² and J³ of the contiguous holding-ratchet and driving-ratchet K and J² will throw the ratchets into the ratchet-wheel; but 70 when turned the other way and from the ratchet-wheel it will strike against the contiguous holding-ratchet lug K³, and lift the ratchet up and away from the ratchet-wheel, and thereby the opposite side lug, K³, of the 75 same holding-ratchet K will strike against the contiguous driving-ratchet J², and lift that ratchet also up and away from the ratchet-wheel.

The adjusting connecting-rod L² is so set 80 and attached to the regulators L that when moved horizontally in direction it will turn one down and the other up, and when moved in the reverse direction it will turn the other down and the one up. Thus the ribbon-spool 85 ratchets may be adjusted by the horizontal movement of the ratchet's connecting-rod so as to move the inking-ribbon in whichever direction desired.

The movement of the carriage M from right 90 to left in writing only by a type-space or letter space distance at a time, and is called the "letter-space" movement. This movement is controlled by the combined apparatus of the right-angled vibratory frame G, the vibratory-frame-holding ratchet U, the toothed racks R R³, and the carriage-driving power S T, and is called the "letter-space" apparatus, and the vibratory frame G is called the "letter-space vibratory frame."

I reserve the right to make the features herein described, but not claimed, the subject of separate applications for Letters Patent.

The invention which is the subject-matter of this application, and what I claim herein, is—

1. The combination of a letter-space vibratory frame, and a driving-ratchet on each side thereof, with a ratchet-wheel on each contiguous ribbon-spool axle.

2. The combination of a letter-space vibratory frame, a driving-ratchet and a holding-ratchet on each side of said frame, with a ratchet-wheel upon each ribbon-spool axle.

3. The combination of a driving-ratchet, a holding-ratchet, and an adjusting-regulator on each side of the letter-space vibratory frame, with said frame and a ratchet-wheel upon the axle of each ribbon-spool.

4. The ribbon-spoils provided with ratchet-wheels and holding-ratchets, in combination with the driving-ratchets on each side of the letter-space vibratory frame, and the adjusting-regulators provided with a connecting-rod, substantially as set forth.

5. The combination of the letter - space ratchet with a toothed rack which is rigidly attached to the carriage, and a like rack which is hinged to hangers which are hinged to the carriage.

GEORGE W. N. YOST.
